UNITED STATES PATENT OFFICE.

WILLIAM T. CARNES, OF KANSAS CITY, MISSOURI, ASSIGNOR TO CARNES ARTIFICIAL LIMB COMPANY, OF KANSAS CITY, MISSOURI.

PHONOGRAPHS.

Application filed December 6, 1922. Serial No. 605,240.

To all whom it may concern:

Be it known that I, WILLIAM T. CARNES, a citizen of the United States, residing at Kansas City, in the county of Jackson and State of Missouri, have invented certain new and useful Improvements in Phonographs; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to phonographs of the type in which a number of record-discs can be placed in a suitable rack or carrier and each record in turn will be placed on the turn-table and revolved, the tone arm swung to position and the needle lowered upon the record; and after the record is played the needle will be raised and the tone-arm swung clear of the record. The record will then be removed from the turn-table and placed in the rack, and another record lifted from the rack and placed on the turn-table; all of which operations will be automatic, and continuous until the machine is stopped by shutting off the power.

The features of this invention are hereinafter fully explained and pointed out, and are illustrated in the accompanying drawings in which:

Figure 1 is plan view of the mechanism of my automatic phonograph, with the cover plate removed therefrom.

Figure 1^a is a plan view of the left hand end of Fig. 1, on an enlarged scale.

Figure 2 is a rear side of the same.

Figure 2^a is a fragmentary section on the line 2^a in Fig. 2.

Figure 3 is a transverse section on the line 3—3 in Fig. 1.

Figure 4 is a section on the line 4—4 in Fig. 1.

Figure 4^a is a section on the line 4—4, showing the left hand half of Fig. 4 on an enlarged scale.

Figure 5 is a section on the line 5—5 in Fig. 1.

Figure 6 is a plan view of the frame of the machine.

Figure 7 is a side elevation of the same.

Figure 8 is an enlarged plan view of a fragment of the mechanism.

Figure 9 is a section of a portion of Fig. 8 on the line 9—9 in Fig. 8.

Figure 10 is a side elevation of the feed mechanism looking in the direction of the arrow in Fig. 8.

Figure 10^a is an end elevation of the feed shaft enlarged.

Figure 11 is a plan of the tone-arm controlling disc.

Figure 12 is a plan of the record carrier ratchet disc.

Figure 13 is a plan of the plane side disc of the friction drive for the carrier.

Figure 13^a is a transverse central section of the friction drive for the record carrier.

Figure 14 is a section on the line 14—14 in Fig. 1.

Figure 15 is a side and an edgewise view of one of the chain links for supporting the record carrier bars.

Figure 16 is a side and an edgewise view of one of the chain links with bracket for supporting large record disc.

Figure 17 is a side elevation of the record stop-plate.

Figure 18 is an end elevation of the same.

Figure 19 is a front view of one of the record lifting chucks with front plate removed.

Figure 19^a is a top or plan view of the hinge mechanism of Fig. 19.

Figure 20 is a vertical central section of the same.

Figures 21 and 22 are side views of the operating cams of the machine.

Figure 23 is a side view of one member of cam #6.

Figure 24 is a section of the same on the line 24 in Fig. 29.

Figure 25 is a side view of another part of the same.

Figure 26 is an edgewise view of said part.

Figure 27 is a side elevation of the double clutch trip mechanism.

Figure 28 is an edgewise view of the internal ring of cam #6.

Figure 29 is a section of said cam on the line 29 in Fig. 24.

Figure 30 is a transverse section of the

turn-table and spindle on the line 30 in Figs. 31 and 32.

Figure 31 is a like section on the line 31 in Fig. 30.

5 Figure 32 is a section of a portion of the frame on the line 32 in Fig. 30.

Figure 33 is a longitudinal section of the tone-arm of my improved phonograph.

10 Figure 34 is a horizontal section of a portion of the same.

Figure 35 is a plan view of the drive-shaft mechanism removed from the machine.

Figure 36 is a longitudinal vertical section of a portion of the same.

15 Figure 37 is an end view thereof looking in the direction of the arrow in Fig. 36.

Figure 38 is a side elevation of the journal bearing for the drive shaft.

20 Figure 39 is an end view thereof looking in the direction of the arrow in Fig. 38.

Figure 40 is a central vertical section of the same in the line 40 in Fig. 39.

In these drawings A, see Figs. 1, 6 and 7, indicates the frame of the machine, which 25 is enclosed within the case of the machine.

At one side of the machine the frame A is at a lower plane than the rest of the frame, in which are shaft bearings A' and A² see Figs. 6 and 7, and mounted in the 30 bearing A' is a short shaft B see Fig. 2^a, which supports a pair of spaced sprocket wheels B'. Mounted in the other shaft bearings A² is another shaft B² upon which is supported and secured a pair of spaced 35 sprocket wheels B³ which are opposite and in line with the sprocket wheels B' at the other side of the machine. Upon these sprocket wheels is a pair of sprocket chains B⁴. The links of these chains are provided 40 with laterally projecting arms b, and b' see Figs. 15 and 16, to which are secured, by rivets or otherwise, segmental cross-bars b², see Figs. 1, 2, and 2^a, there being sufficient space between adjacent bars b² to receive a 45 record disc b³ and b⁴ as shown in Fig. 2.

The arms b' of the chain links are provided with a laterally extending bracket b⁵ on each side of the carrier, which brackets receive the lower edge of the large sized 50 record discs. The segmental cross-bars secured to the arms b on each alternate chain link, are provided with brackets b⁶ which are secured to the inner surface of the segmental cross-bars see Fig. 14, and project 55 through openings in the side walls of said bars so that they will engage the lower edge of small sized records when placed in the carrier.

60 The shaft B² is also journalled in a downwardly extending part a, of the frame A, and is provided with a frictionally driven ratchet wheel C, see Fig. 13^a, which is secured on said shaft between the discs C' and C², with intervening discs of packing c c between them. The discs C' and C² are pro-

vided with hubs c' by means of which they are non-rotatably secured to the shaft B² by means of transverse pins c² and c³, the pin c³ passing through a slot in the shaft B². The end of the shaft B² is hollow and 70 is closed by means of a screw-plug C³, and a spring c⁴ is placed between the screw-plug C³ and the pin c³, so as to press against said pin and thereby press the disc C² toward the disc C' and thereby compress the layers of 75 packing c c against the ratchet wheel C so that there will be sufficient friction to cause the shaft B² to rotate to cause the endless record carrier to move as hereinafter described.

80 The disc C', see Fig. 11, is provided, around its periphery, with twelve ratchet notches, six of which, c⁵ are not cut as deep as the remaining six notches c⁶. The purpose and operation of these notches c⁵ and c⁶ will be fully explained hereafter.

85 At the intermediate part of the frame A, see Figs. 6 and 7, are provided journal bearings A³ and A⁴, in which are placed rock-shafts D and D' of swinging brackets D² and D³ see Figs. 1, 4, 14, 19^a, and 30. These rock-shafts D and D' are secured against longitudinal movement by means of rings d placed on their inner ends, and secured thereon by means of set-screws d'. The rings d are provided with arms d² and d³ 90 see Fig. 32.

95 Attached to the arms d² and d³ are springs d⁴ and d⁵ which have their opposite ends secured in ears a' on the frame A so that the action of said springs tends to swing the brackets D² and D³ upwardly. At each side of the axes of rock-shafts D and D' on the opposite sides of the frame A are stops, a², against which the brackets D² and D³ contact to limit the downward and upward movement of said bracket.

100 The swinging brackets D² and D³ are provided at their outer ends with one member of a vertical stop hinge, D⁴, see Figs. 1, 4, 14, 19. Pivoted on the hinge part D⁴, by means of a hollow hinge pin d⁶ are hinge lugs E and E' of record lifting chucks E² and E³, the chuck E² being adapted to lift 110 the records from the carrier bars b² and the chuck E³ being adapted to replace the records back in the carrier bars, working alternately.

115 In the hinge part D⁴ is placed a spring D⁵ in the manner usual in such hinges, which operates to maintain the hinge normally open as shown in Figs. 1 and 19, and when the hinge is operated as hereinafter described, assists in lifting the chuck bodies 120 back to their normal position.

125 These lifting chucks E² and E³ are duplicates, with the exception that their construction is reversed, so that they face each other. Their construction is as follows, reference 130 being had to Figs. 19 and 20, viz:

They are preferably partly circular, and bowl shaped, with a segmental indentation at the lower edge to permit of the passage thereunder of the segmental carrier bars b^2 as shown in Fig. 4. The inner face thereof is provided with three pairs of radial boss-ribs e between which are pivoted record gripping hooks e' and e^2 , which are operated by means of connecting bars e^3 . Pivoted in the center of the chuck body is a shaft E^4 which is provided with three radial arms e^4 from each of which link bars e^5 extend to and are pivoted to the ends of the connecting bars e^3 . A spring E^5 is provided to operate the gripping hooks e' and e^2 to engage a record disc. The shaft E^4 is provided with an arm e^6 from which a link-bar e^7 extends to one arm of a bell-crank lever E^6 pivoted at the periphery of the chuck body, the other arm of which extends over the upper end of the hollow hinge pin d^6 . When the bell-crank lever E^6 is operated, as hereafter described, to rock the shaft E^4 against the action of the spring E^5 the gripping hooks e' and e^2 will swing outwardly from the center of the chuck body, the hooks e^2 completely receding back of the face of the chuck, and the hooks e' swinging out into gripping position. If a large record is presented to the chuck, the hooks and the mechanism released to the action of the spring E^5 the hooks e' will grip the edges of the record.

If a small record is presented, the hooks e' will swing inward as shown in Fig. 20, and the hooks e^2 will grip the edge of the record.

The face of the chuck is covered by a plate e^8 which is secured in place by means of screws e^9 see Fig. 20 and which plate is provided with slots through which the record gripping hooks e' and e^2 operate.

Pivoted in the lower side of the swinging bracket D^2 is a bell-crank lever F , one arm of which extends under the lower end of the hollow hinge-pin d^4 , and in said hinge-pin is a rod d^5 which extends from said bell-crank lever upwardly to the end of the bell-crank lever E^6 so that when the bell-crank lever F is operated the movement is communicated to the chuck mechanism hereinbefore described.

Upon stud-shafts F' and F^2 secured in the machine frame A , are bell-crank levers f , f' , and from one arm of each bell-crank lever f a link f^2 extends to the upwardly extending bell-crank lever F , and from one of each bell-crank levers f' links f^3 extend to ears f^4 on the lower hinge-lugs E' of the lifting chucks E^2 and E^3 . The ends of the arms of the bell-crank levers f and f' to which the links f^2 and f^3 are pivoted, are on the line of the axis of the rock shafts D and D' so that when the chucks E^2 and E^3 are swung upwardly as hereinafter de-

scribed, the links f^2 and f^3 swing simultaneously without interference to their operation.

Mounted in a vertical journal bearing G in the frame A , is a spindle G' for a turn-table G^2 . This spindle G' is provided with a hub G^3 at its upper end, around which is formed skew gear teeth. Above the hub G^3 is a friction disc g , upon which the turn table G^2 rests. The under side of the turn table is preferably provided with a recess to receive the friction disc, g , and by which it is centered on the spindle. The lower end of the spindle G' stands upon a ball g' , see Fig. 30, which rests upon a screw-plug g .

In Figs. 35 and 36 I show a shaft mechanism for operating the several mechanisms of this machine which consists of the shaft H which is mounted in a suitable bearing a^3 on the frame A . This shaft is provided with a thrust ring h , which enters a recess in the outer end of the bearing a^3 , and a ring a^4 is placed on the shaft H and secured against the outer end of the bearing a^3 to secure the shaft H against longitudinal movement in the bearing. Upon the shaft H , I place a sleeve H' which is provided with a thrust flange h' which enters a recess on the inner end of the bearing a^3 , and is retained therein by a ring, a^5 , which is secured on the inner end of the bearing a^3 , preferably by bolts which pass through the body of the bearing a^3 and ring a^4 and are threaded into the ring a^5 , so that the sleeve H' is secured against longitudinal movement, but is free to revolve.

Adjacent to the inner end of the sleeve H' there is a worm thread h^2 , and on the inner end of the sleeve H' are radial ratchets, or clutch teeth h^3 . Upon the shaft H , I then place a slidable sleeve clutch H^2 , through the walls of which are longitudinal slots h^4 , through which a transverse key h^5 , passes, said key also passing through the shaft H , in which it is secured by a set-screw H^3 . The slots h^4 , in the sleeve H^2 being long enough to permit the clutch sleeve H^2 to slide as hereinafter described. Each end of the sleeve H^2 is provided with radial ratchet clutch teeth h^6 which are adapted to engage the teeth h^3 and the sleeve H' .

Upon the inner end of the shaft H , I place a sleeve-shaft H^4 , one end of which is provided with radial ratchet teeth H^5 adapted to be engaged by the teeth h^6 on the end of the clutch sleeve H^2 , and adjacent to said teeth H^5 is a worm thread H^6 , and at the opposite end I provide a worm thread H^7 , and a spindle h^7 with a threaded end upon which is placed a nut h^8 . The end of the shaft sleeve H^4 extends into the spindle bearing G , the worm thread H^7 engaging the skew gear teeth G^3 on the hub of the

spindle G' as shown in Fig. 31. The spindle h' on said shaft sleeve having a bearing in the opening g' in the spindle bearing G, see Fig. 32, and the nut h' prevents longitudinal movement thereof, as shown by broken lines in Fig. 1. Upon the outer end of the shaft H, I place a pulley H', upon which a belt, J, shown in broken lines, is placed, which is operated by a pulley J' on a motor J'. When the clutch sleeve H' is in the position shown in Fig. 35, and the motor is started, the sleeve shaft will revolve and cause the turn-table to revolve.

Under the turn-table there is the usual horn or resonator, J', and upon the upper end of this resonator is the swivel J' for the tone arm J'. This swivel J' is constructed as follows, reference being had to Fig. 33, viz:

Upon the upper end of the resonator J' is placed a ring j which is provided with spokes j' at the intersection, or hub, of which is a vertical tube j', and upon this ring j, is placed a ring of felt j'. Upon the ring j' is placed another ring j' which has an internal spider j' which supports a vertical tube J' which receives the tube j' and swings thereon. The ring j' is provided with clamp-ears j' through which a clamp-screw j' passes to secure the tone-arm J' firmly therein.

The ring j' is provided with an arm J' by which the ring j' and tone-arm J' are operated as hereinafter described.

The tone arm J' is provided with a vertically hinged extension J' which is adapted to swing upon the pivot screws j', and upon this extension the sound box is secured. Within the tone arm is a needle lifting lever K' which is pivoted to the hinged extension J', back of the pivot screw j', and has a short end k which engages the upper wall of the hinged extension. The long end of this lever extends backward to a point directly above the upper ends of the tubes j' and J', and from this lever a cord k' extends downwardly through said tubes, and through the resonator J', shown by broken lines in Fig. 5, the lower wall (not shown) being provided with an opening for said cord for the purpose hereinafter described.

The mechanism I have designed for actuating the several mechanisms hereinbefore described, consists of a cam-shaft L, which is provided with a worm gear wheel L' see Figs. 1, 3 and 5, which intermeshes with the worm thread h' on the sleeve H', see Fig. 35, by means of which gear the cam shaft L is caused to rotate. Upon this cam shaft L are a series of cams, numbered 1 to 11 inclusive, see Fig. 3, and 21 to 26 inclusive. These cams are so adjusted on the shaft L with relation to each other that the mechanism actuated thereby, will move in timed sequence with relation to each other

as will be hereinafter described. The cam-shaft L is mounted in suitable bearings L' on the machine frame A, see Fig. 3. L' see Figs. 1, 4, 5, 14 indicates a transverse shaft secured in the bearing blocks L' parallel 70 with the cam-shaft L, and does not rotate. Upon this non-rotatable shaft L' are cam-levers 1' to 11' inclusive, see Figs. 21 and 22, which illustrate the association of said cams and levers.

M indicates a feed shaft see Figs. 1, 3, and 8 which is mounted in the bearing blocks L' in the frame A, and is provided with a worm gear M' which meshes with the worm H' on the shaft H', and said worm gear wheel being on the side of the shaft H' opposite to the worm gear wheel L', is rotated by said shaft in a direction opposite to the direction of rotation of the worm gear L'. The feed shaft M is provided with a sleeve M' which is free to rotate on said shaft. This sleeve M' has secured thereon a cam sleeve M' which has cam edges m, m, against which a spring pressed roller N operates for the purpose of insuring the coming to rest of the sleeve M' with the short arm m' in the position thereof shown in Fig. 8. The sleeve M' is provided with annular clutch teeth, m'. Upon the feed shaft M are splines m', see Figs. 8 and 10, upon which a sleeve M' is slidably placed, so that when the shaft M revolves, the sleeve M' must revolve with it. The sleeve M' is provided with annular clutch teeth, m', which are adapted to engage the teeth M' on the sleeve 100 M' as hereinafter described. Upon the shaft M between the adjacent ends of the sleeves M' and M' is a spring M'. The sleeve M' is provided with screw-threads m' for the purpose hereinafter set forth. Pivoted in 105 the frame A is a U-shaped bracket O, by means of a pin O', and between the arms of said bracket a sleeve O' see Figs. 9 and 10 is mounted on a pin o. Upon the sleeve O' a gear segment O' is secured which 110 meshes with the screw-threads m' on the sleeve M'. The hub o', see Fig. 10, of the segment O' is provided with stud posts o' and o'. Secured to the frame A is a stationary bracket N' see Fig. 8 which is adapted to engage the stud post o' on the hub o' of the segment O' when the swinging bracket O moves to the position shown by broken lines in said Fig. 8, for the purpose 115 hereinafter described. Secured on the sleeve O' by means of the clamp n, is an arm N', in the free end of which is pivoted a link N', the adjustment of the angular relationship of said arm N' and link N' being regulated by means of a thumb screw n', for the 120 purpose hereinafter described. The link N' is provided with a segmental plate N', having thereon a graduation to indicate the degree of angularity between the arm and link.

In the end of the link N^3 a rod N^5 is pivoted which extends to the arm J^7 see Figs. 1 and 33, on the tone arm swivel, so that by means of the operation of the screw threads m^6 on the sleeve M^4 and the segmental gear O^2 , the tone arm J^5 is operated as hereinafter described.

In the lower end of the cam lever 1^a a rod n^2 , see Figs. 5 and 9, is pivoted, which extends to and is pivoted to the swinging bracket O , so that when cam 1 operates the cam lever 1^a the swinging bracket O is caused to swing to the position thereof shown by broken lines in Fig. 8. The swinging bracket is moved in the opposite direction by a spring o^4 , see Figs. 3 and 5, which is attached to the frame A . Pivoted to the cam lever 2^a is a rod P , see Fig. 5, which is connected to a lever P' by means of an adjusting swivel p . The lever P' is fulcrumed on bracket p' which is secured on the frame A , and extends under the resonator J^3 , where the cord k' see Fig. 33 is secured thereto, so that when the cam lever 2^a is operated by the cam 2 the sound box K will be raised sufficiently to lift the needle out of contact with the record disc on the turn table G^2 , as shown by broken lines in Fig. 33.

To the cam lever 3^a is pivoted a rod P^2 by means of an adjustment swivel, which rod extends and is pivoted to the bell-crank lever f see Figs. 19 and 19^a, by means of which, when the cam lever 3^a is operated by the cam 3, the record gripping mechanism in the lifting chuck E^3 will be operated, as hereinbefore described.

To the cam lever 4^a a rod P^3 extends and is pivoted to the bell-crank lever f' see Figs. 19 and 19^a, so that when the cam lever 4^a is operated by the cam 4, the power is exerted through the link f^3 , see Fig. 19^a, to cause the lifting chuck E^3 to swing from a vertical to a horizontal position on the swinging bracket D^3 , see Fig. 1 so that said bracket will be stopped by the lug a^2 at the left of the rock shaft D' .

To the lower end of the cam lever 5^a a rod P^4 is pivoted and extends to and is pivoted to an ear p^2 , see Fig. 19^a, on the upper side of the swinging bracket D^3 see Figs. 1, and 19^a so that when the cam lever 5^a is operated by the cam 5, the swinging bracket D^3 will raise the lifting chuck E^3 to a vertical position.

Cam lever 6^a is secured upon a shaft Q mounted in the two intermediate bearing blocks L^2 on the frame A , and on the rod Q is a yoke Q' , see Figs. 35, 36, and 37, for shifting the slideable clutch H^2 on the drive-shaft H , out of engagement with the shaft H^4 and into engagement with the sleeve H' , for the purpose hereinafter described, so that when the cam lever 6^a is operated by the engagement therewith of the short arm

m^4 on the sleeve M^2 the cam lever 6^a will cause the clutch sleeve H^2 to be disengaged from the shaft H^4 and to become engaged with the sleeve H' , so that the cam shaft L will be operated as described, hereinbefore, 70 which operation will continue until cam 6 engages said cam lever 6^a and operates the same to again shift the clutch sleeve H^2 into engagement with the shaft H^4 .

On the shaft Q is an arm Q^2 , see Fig. 27, 75 which is provided with inclined surfaces on the upper end thereof which meet on the center line thereof, and above the upper end of said arm is a spring pressed lever Q^3 , provided with a roller q in the end thereof of which operates to cause the arm Q^2 to throw the clutch sleeve either way, longitudinally.

The construction of the cam 6, is as follows, see Figs. 23, 24, 25, 26, 28, and 29. 85 There are two parts; q' and q^2 . The part q' is non-rotatably secured upon the cam shaft L by means of a transverse pin through said shaft. At each side of the part q' are discs g^2 which rotate on the cam shaft L^3 which connects said discs g^2 to the cam lobe q^3 , which operates in a recess q^4 , see Fig. 24, in which is placed a spring q^5 to yieldingly maintain the lobe in the position shown in said figure. Now as the cam shaft L rotates the cam 6 in the direction shown in Fig. 22 it engages the cam lever 6^a and operates said lever until the lobe q^3 passes the lever 6^a when the spring q^5 throws the lobe clear of the end of the lever 6^a so that it can 100 be swung back to its normal position by the arm Q^2 ; this is necessary because at the instant the arm q^2 operates to throw the clutch sleeve H^2 the cam shaft L and cams cease to revolve.

Pivoted on the lever 7^a is a rod p^5 which extends and is pivoted to the swinging arm p^3 see Fig. 5 mounted on the shaft B^2 upon which is pivoted a spring pressed ratchet dog p^4 which is adapted to engage the 110 ratchet teeth on the friction disc C , see Fig. 3.

The cam 7 first engages the roller in the short arm of cam lever 7^a , see Fig. 22 which causes the swinging arm p^3 to swing upwardly so that the dog p^4 will engage the second tooth on the disc C , and continuing its revolution the cam 7 engages the roller in the long arm of said cam lever and forces it downward, which through the rod p^5 and dog p^4 causes the disc C to revolve which by means of the friction caused by the discs C' and C^2 , see Fig. 13^a causes the shaft B^2 to move the record carrier forward until the travel thereof is stopped by a record disc b^4 125 therein, see Fig. 2, engaging the plate R , see Figs. 14, 17 and 18, hereinafter described, which causes the record carrier to stop its travel, the friction between the discs C , C' and C^2 allowing the disc C to continue its 130

travel until the cam 7 releases the cam lever 7^a.

- 5 To cam lever 8^a a rod P⁵ is pivoted which extends and is pivoted to a bell-crank lever 5 R', see Fig. 14, which is pivoted in a vertical slot r in the frame A. Supported on the axle B, of the carrier, see broken lines in Fig. 2, and full lines in Fig. 2^a by means of a bell-crank lever r', and supporting arms 10 r² at each end thereof, is a plate R, which extends upwardly far enough to be engaged by the lower edge of each record disc b³ or b⁴ when they are carried toward the lifting clutch E². The other arm of the bell-crank 15 lever r' rests upon the free arm of the bell-crank lever R', so that when the cam lever 8^a is actuated by the cam 8, the plate R will be slightly swung against the lower edge of the record disc and cause the upper edge of 20 the same to be pressed snugly against the lifting clutch E² so that the gripping hooks e and e', see Figs. 19 and 20, will firmly grip the edges of the record disc when the same operates as hereinbefore described.
- 25 To the lower end of the cam lever 9^a, a rod P⁶ is pivoted and extends to an ear p² on the upper side of the swinging bracket D² at the upper side of Fig. 1, see Fig. 19^a, so that when said cam lever 9^a is actuated by 30 cam 9 said swinging bracket D² with the lifting clutch E² is swung to a vertical position as shown by broken lines in Fig. 4.

Pivoted to the lower end of cam lever 10^a is a rod P⁷ which extends and is pivoted to 35 a bell-crank lever f' at the upper side of Fig. 1 see Fig. 19^a, as and for the purpose hereinbefore described, so that when said cam lever 10^a is actuated by cam 10, the lifting chuck E² will be caused to swing on its 40 hinged joint from the vertical position shown by broken lines in Fig. 4, to a horizontal position shown by broken lines in Fig. 2, over the turn table G².

To the lower end of cam lever 11^a a rod 45 P⁸ is pivoted, and extends and is pivoted to a bell-crank lever f. The free end of said bell-crank lever has a link f² which operates the mechanism for actuating the gripping mechanism of the lifting chuck as herein- 50 before described.

The turn table G² is provided with an annular groove g⁴ which is to give clearance for the gripping hooks e² in the lifting chucks when a ten inch record disc is 55 to be placed or removed from the turn table. The twelve inch record discs extend sufficiently over the periphery of the turn table to give the necessary clearance.

The pitch of the thread m⁶ on the feed 60 worm sleeve M⁴ is such that during the playing of a record, the tone arm J⁵ will follow the spiral music-groove in the record, but when the needle enters the final groove and is circular instead of spiral, which is 65 somewhat deeper than the music groove,

there will be sufficient back-pressure, or resistance offered thereby to the swing of the feed-segment O³ to cause the worm-sleeve M⁴ to move longitudinally on the splined feed shaft M to compress the spring M⁶ and permit the annular clutch teeth m⁵ thereon to engage the annular teeth m² on the sleeve M² which causes the sleeve M² to revolve therewith until the reversing arm m' thereon engages and operates the reversing cam lever 6^a as hereinbefore described, which causes the feed mechanism to stop with the arm N² in the position shown by full lines see Fig. 8 and causes the cam shaft mechanism to start. After 70 the sound box has been lifted as hereinbefore described, cam 1 operates to cause the swinging bracket to move to the position shown by broken lines, which causes the arm N² to swing to the position shown by broken lines in said Fig. 8, thus causing the tone arm J⁵ to swing clear of the turn table G² as indicated by broken lines in Fig. 1, and hereinbefore described.

Pivoted on a pin, S secured in the frame A, see Fig. 5, is a bell-crank lever S' which is provided with a spring s to yieldingly maintain one arm of said lever S' in contact with the disc C', so that it will engage the ratchet teeth c⁵ and c⁶ on the periphery of said disc hereinbefore described. When the disc C' is caused to revolve by the ratchet disc C, as described, and the arm of the bell-crank lever drops into one of the shallow notches c⁵ in the disc C', said lever compresses the spring S² on a rod S³, see Figs. 3 and 8, which rod is pivoted to a lever s' which is pivoted upon the frame plate A⁵, see Figs. 3, 8 and 9, by the pivot pin s². This compression of the spring S² forces the lever s' against a stop-post s³, see Fig. 8, secured in said frame plate A⁵, thereby limiting the lateral movement of said lever s' so that the opposite end of said lever, shown in broken lines 90 Fig. 8, will engage the stud post o³, see Fig. 10, on the hub o' of the gear-segment O³, when the swinging bracket O is returned to the position shown in full lines in Fig. 8, which thereby places the segment O³ in 95 mesh with the threads m⁶ on the feed sleeve M⁴ with the tone arm J⁵ in position to drop the needle about one eighth of an inch inside of the periphery of a ten inch record disc.

At the next movement of the disc C' the bell-crank lever, will drop into a deep notch c⁶ in the periphery thereof, which will cause said lever to contact with the adjusting nut S⁴, on the rod S³, and thereby cause the lever s' to swing to the position thereof shown by broken lines in Fig. 8, against the stop-post s⁴ secured in said frame plate A⁵, so that the free end of said lever s' will engage the stud-post o³ 100 105 110 115 120 125 130

in the hub o' of the segmental gear O^3 , but not to the same extent as when said lever is swung to the opposite position, so that said stud-post will slip out of engagement therewith sooner, so that the gear segment O^3 will sooner mesh with the threads m^6 on the feed sleeve M^4 , thus placing the tone arm J^5 in position to drop the needle on or about one eighth of an inch inside of the periphery of a twelve inch record disc. It will thus be seen that the shallow notches c^5 in the disc C' have relation to the small records, and the deep notches c^6 have relation to the large record discs, and that the 15 large and small records may alternate with each other in the carrier.

I have provided a cut out mechanism by means of which the automatic mechanism hereinbefore described will be caused to remain inactive, so that record discs can be placed upon and removed from the turntable by hand, which is as follows, viz:

A lever T is pivoted upon the frame A by means of a pivot t , which is adapted to be swung laterally to engage the swinging bracket O , and prevent its return from the position thereof shown in broken lines in Fig. 8, to the position thereof shown by full lines, which prevents the segment O^3 from meshing with the worm threads on the feed sleeve M^4 , so that the segment O^3 , and arm N^2 will swing freely as the needle, travelling in the music groove on the record disc, causes the tone arm J^5 to swing. The lever 35 T can be clamped in any position by means of a thumb nut T' see Figs. 5, 8 and 9, upon the upper end of the operating rod T^2 which projects through a slot in the plate T^3 secured upon the cover-board T^4 of the machine. The rod T^2 is provided with a disc t' which operates against the under side of the slotted plate T^3 when the nut T' is screwed down to clamp the cut out mechanism fast.

Pivoted in the frame A see Figs. 8 and 9, is a swinging stop bracket U which is operated by means of a link U' pivoted thereto and to the lever T , the lower arm u thereof being adapted to engage the gear segment O^3 for the purpose of limiting the movement thereof when the needle has reached the last music groove in the record. The position of this stop bracket is fixed by the position at which the lever T is clamped by the thumb nut T' so that when the tone arm J^5 has been swung by the needle in the music groove on the record disc to the limit of its required travel, the segment O^3 will engage the lower arm u on the stop bracket U , and limit the swing of said segment, and the continued rotation of the feed sleeve M^4 will cause it to move longitudinally until it engages the sleeve M^2 for the purpose of reversing the mechanism as hereinbefore described, so that there will be no danger of

the last groove on the record disc not stopping the feed mechanism.

As some record discs have music grooves on one side only, and because after a single sided record has been played and placed back in the carrier rack by the lifting chuck E^3 , the blank side of said record will be up when it is again placed on the turn table by the lifting chuck E^2 it is necessary to cut an annular groove in the blank side of said record disc, near the periphery thereof, into which the needle will enter and owing to the resistance offered by the groove so cut, the feed mechanism will be reversed as hereinbefore described, and the lifting chuck E^3 will operate to take said record off of the turn table, and the lifting chuck E^2 will then put the next record disc upon the turn table. For the purpose of cutting these annular grooves in the blank sides of record discs, I pivot to the machine frame A , by means of the pivot V an arm V' in which are secured cutting tools V^2 and V^3 , see Figs. 1 and 5, which are adapted to cut properly shaped grooves into the record discs at the required position on the record disc, the tool V^3 being to cut a ten inch record disc, and the tool V^2 to cut a twelve inch record disc. Adjacent to each of these cutting tools are rollers V^4 and V^5 which are for the purpose of gauging the depth of the grooves cut by the tools V^2 and V^3 . The roller V^4 is made larger than the roller V^5 so that the tool V^3 will be sustained out of contact when a groove is being cut on a twelve inch record.

In operation, a small record is placed on the turn table G by hand, and thirteen alternate large and small records b^3 and b^4 are placed in the carrier mechanism in a vertical position as shown in Fig. 2, with the record sides, desired to be played, toward the lifting clutch E^2 . We will assume that the reversing clutch is in the position shown in Fig. 35, ready to start the turn table in action, and the tone arm in the position indicated by broken lines in Fig. 1. The cam shaft L is just finishing its revolution prior to being stopped by the action of cam 6, upon the double reversing cam lever 6^a , and cam 1 has released the swinging bracket O to place the segment gear O^3 in mesh with the feed-sleeve worm threads, m^6 which causes the tone arm to swing over so that when cam 2 releases cam lever 2^a the sound box K will lower the needle upon the record disc just outside of the first music groove. The cam shaft is by this time at a stand still, and the turntable is revolving, and the feed-shaft M is revolving the feed sleeve M^4 and thereby operates the segment gear O^3 to feed the tone arm J^5 toward the music groove of the record. When the needle has traversed the music groove to the end thereof, the gear segment O^3 will engage the stop u

see Fig 8, just as the needle drops into the circular groove at the end of the music groove. The reversing mechanism is then operated as hereinbefore described, and the 5 cam shaft started in motion. Cam 2 then operates to cause the sound box to raise the needle off of the record disc, cam 1 operates to swing the bracket O, segment O³ and arm N² to the position thereof shown by broken 10 lines in Fig. 8, which causes the tone arm J⁵ to swing clear of the record disc on the turn table, as indicated by broken lines in Fig. 1. Cam 5 then operates to swing the lifting chuck E² to a vertical position, when 15 the same is lowered to a horizontal position over the turn table, by cam 4. Cam 3 next operates to release the gripping hooks e and e' to the action of the spring E⁵, see Fig. 20, as hereinbefore described, so that said 20 hooks will grip the edge of the record on the turn table G. Cam 4 then operates to raise the chuck E² to a vertical position with the record disc securely gripped there- 25 to from which position it is lowered to the position shown by full lines in Figs. 1, 2 and 4, with the record disc placed in vertical position in the carrier. Cam 3 then operates to release the gripping hooks from the edge 30 of the record disc, when cam 7 operates to cause the carrier to move forward one step, or more thus causing the record disc just taken from the turn table to move forward away from the face of the lifting chuck E², and at the same time carrying 35 the next record disc, to be played, up to the lifting chuck E² in position to be gripped thereby. Cam 8 next operates the plate R, so that the same will press against the lower 40 edge of the next record to be played, so as to swing its upper edge against the face of lifting chuck E². Cam 11 now operates to release the gripping hooks e and e' to the action of spring E⁵ see Fig 20, so that they will grip the edge of the record disc. Cam 45 9 now operates to raise lifting chuck E² to a vertical position, when cam 10 operates to swing it to a horizontal position over the turn table with the central opening therein over the upper end of the turn table spindle, 50 when cam 11 operates to release the grip of the hooks e and e' from the record disc. Cam 10 now causes the lifting chuck to return to a vertical position leaving the record disc upon the turn table, from which 55 position the lifting chuck E² is caused to swing back to its position over the carrier by cam 9, ready to receive the next succeeding record.

The action of the cam shaft is now 60 stopped as hereinbefore described, and the power is shifted to the playing mechanism, as hereinbefore described.

If a blank side of a record happens to come up when placed on the turn table, the 65 groove cut thereon as hereinbefore de-

scribed, will cause the mechanism to operate to remove said record from the turn table and place it back in the carrier, as described.

Having thus fully shown and described 70 the construction and operation of the several parts of my invention, and the general operation of the same as a whole, I do not desire to limit myself to the exact construction and arrangement shown and described, 75 as most desirable, as many changes and modifications can be made therein without departing from the scope of my invention. Therefore what I claim as new and desire to secure by Letters Patent is: 80

1. In a machine of the class described, an endless record-disc carrier adapted to receive and support a plurality of record-discs, a turn table, mechanism to lift a record-disc from said carrier and place it 85 on said turn table, a tone reproducing mechanism including a needle adapted to travel the tone groove on said record-disc, clutch mechanism in the turn-table operating mechanism, mechanism adapted to be 90 operated by the tone reproducing mechanism to operate said clutch mechanism to release the power from the turn-table operating mechanism when the needle has traveled to the end of the tone groove, mecha- 95 nism adapted to lift the needle and swing it clear of the record-disc, mechanism adapted to remove said record-disc from the turn-table and place it in said record-disc carrier, and means to actuate said mechanisms 100 in timed sequence with relation to each other.

2. In a machine of the class described, an endless record-disc carrier adapted to receive and support in vertical position a plurality of record-discs, a turn-table, mechanism adapted to lift a record from said carrier and place it upon said turn-table, mechanism adapted to move said carrier forward one step, tone reproducing mechanism 105 including a needle adapted to travel the music groove in a record-disc mechanism adapted to swing said needle over said record-disc and lower it upon the same, mechanism to disengage the power from the turn-table operating mechanism, mechanism to swing said needle clear of the record-disc after it has traveled to the end of the music groove, mechanism to actuate the record-disc removing mechanism, and cam mechanisms adapted to cause all of said mechanisms to operate in timed sequence with relation to each other. 115

3. In a record-disc carrier for phonographs, a pair of endless chains, sprocket 125 wheels to carry said chains, means supported on said chains to support record-discs in a vertical position, and mechanism adapted to impart step-by-step motion to said chains.

4. In a record-disc carrier for phon- 130

graphs, a frame, shafts journaled therein, a pair of sprocket wheels supported on each of said shafts, a pair of endless chains on said wheels, brackets on each link of said chains, traverse bars secured on said brackets bridging the space between said chains, projections on said bars and brackets adapted to engage the lower edges of record-discs placed between said bars, and mechanism 10 to impart step-by-step motion to said chains.

5. In a record-disc lifting mechanism for phonographs, a chuck body, a plurality of record-disc gripping hooks mounted therein and adapted to swing outwardly through the face thereof, and mechanism adapted to operate all said hooks simultaneously.

6. In a record-disc lifting mechanism for phonographs, a chuck body, a plurality of pairs of record-gripping hooks some of which are adapted to swing into gripping position while others of said hooks remain within said chuck body, and spring actuated mechanism adapted to cause some of 25 said hooks to move into gripping position.

7. In a record-disc lifting mechanism for phonographs, a chuck body, hooks pivoted therein so as to swing through the face of said chuck body, a shaft centrally mounted 30 in said chuck, radial arms on said shaft, link bars extending from said arms to said hooks, a spring to operate said shaft in one direction, and means to mechanically operate said shaft in the other direction.

35 8. In a machine of the class described, one endless record-disc carrier adapted to receive a plurality of record-discs and support them in a vertical position, a frame, traverse shaft bearings in said frame, rock-shafts in said bearings, swinging brackets secured on said rock-shafts, lifting chucks hinged on said swinging brackets and supported thereby over said record-disc carrier and adjacent to each end thereof, and cam 40 actuated mechanisms to operate said endless carrier forward step-by-step and to operate said lifting chucks and their gripping hooks, all in timed sequence with relation to each other.

50 9. In a machine the class described, a turn-table, means to rotate said turn-table, a record-disc carrier, a record-disc lifting chuck adapted to grip the edge of a record-disc and transfer it from the carrier to said turn-table, ratchet mechanism adapted to move said record-disc carrier forward one step, a record-disc-lifting chuck adapted to grip the edge of a record on said turn-table and transfer it to said carrier, and cam 55 actuated mechanisms to actuate said lifting chucks and said ratchet mechanism, in timed sequence to each other.

60 10. In a tone arm positioning mechanism for a phonograph, a feed shaft, a gear mechanism for rotating the same, a feed sleeve

on said shaft, a trip arm on said sleeve, a spring pressed worm sleeve slidably and non-rotatably mounted on said feed shaft adapted to engage and disengage said feed sleeve, swinging bracket, a gear segment 70 adapted to be operated by said worm sleeve pivoted in said swinging bracket, a stud-post on the hub of said gear segment, a stationary bracket adapted to be engaged by said stud-post, an arm on the pivot of 75 said gear segment, a tone arm, means to connect said arm with said tone arm, means to limit the travel of said segment so that the co-operation of said worm-sleeve and segment will cause said worm-sleeve to engage and rotate said feed-sleeve, a driven-shaft, a worm-sleeve thereon, a cam shaft, a worm-gear thereon intermeshing with said worm-sleeve, a slideable clutch sleeve on said driven shaft, means adapted to be operated 80 by the trip arm on said feed-sleeve to slide said chuck sleeve into engagement with the worm-sleeve on said driven shaft, means adapted to be operated by the trip arm on said feed sleeve to slide said clutch sleeve 85 into engagement with the worm sleeve on said driven shaft, means adapted to be operated by a cam on said cam-shaft to operate said swinging bracket to disengage said segment from the first mentioned 90 worm-sleeve and cause said stud-post to engage said stationary bracket and thereby to cause said tone arm to swing to its starting position, and a cam on said cam shaft adapted to actuate said clutch operating 95 mechanism to release the power from said cam-shaft.

11. In a machine of the class described, a turn-table to receive a record-disc, means to rotate the same, a tone-arm carrying a 105 sound box and needle secured therein, worm and gear mechanism adapted to feed said tone arm in unison with the spiral music groove on a record-disc, means to limit the movement of said worm and gear mechanism, a driven shaft, clutch mechanism on said driven shaft, a cam shaft adapted to be operated by said clutch mechanism, means to be actuated by said worm and gear mechanism to operate said clutch 110 mechanism, a cam on said cam shaft, mechanism adapted to be operated by said cam to disengage said worm and gear mechanism, another cam on said cam shaft, and means adapted to be operated thereby to release said clutch mechanism to stop said cam shaft.

12. In a machine of the class described, a turn-table to receive a record-disc, means to rotate said turn-table, a tone arm comprising a sound box and needle pivoted adjacent to said turn-table, a driven shaft, a pair of worm-sleeves on said driven shaft, a slideable clutch sleeve non-rotatably mounted on said driven shaft between said worm- 125 130

- 5 sleeves and adapted to alternately engage the same, a feed-shaft, a worm-gear wheel thereon intermeshing with one of said worm sleeves, a cam shaft, a worm-gear thereon 5 intermeshing with the other of said worm sleeves, mechanism operated by said feed shaft to feed said tone arm forward in unison with the travel of the needle in the spiral music grooves in a record-disc on said 10 turn-table, means to cut the power off from the said turn-table when the needle has reached the end of the music groove on a record-disc, means to limit the action of the feed mechanism, means operated by said 15 feed-shaft to operate said clutch to stop the rotation of the feed-shaft and start the rotation of the cam-shaft, a cam on said cam-shaft, mechanism operated thereby to disengage the feed mechanism and operate 20 the same to swing said tone-arm clear of the record on the turn-table, and afterward swing it back to starting position, and another cam on said cam-shaft adapted to operate said slidable clutch to stop the cam- 25 shaft and start the feed shaft.
13. A travelling record-disc carrier, adapted to support alternately large and small record-discs, a shaft to operate the same, a disc non-rotatably secured on said shaft 30 having alternate shallow and deep cam notches in the periphery thereof, a turn-table, means to rotate the same, cam actuated mechanism adapted to transfer a record from said carrier to said turn table, 35 and like mechanism to transfer said record-disc back to said carrier, a feed-shaft, a tone-arm pivoted adjacent to said turn-table, gear and lever mechanism adapted to be operated by said feed-shaft to cause said 40 tone arm to swing in unison with the spiral music groove on a record-disc, cam actuated mechanism to disengage said gear mechanism and swing said tone arm clear of said turn-table, and means operated by 45 said cam notches to cause said gear mechanism to become reengaged and swing said tone arm back to the desired starting position with relation to the edge of a large or small record disc on said turn-table.
14. In a record-disc carrier actuating 50 mechanism, a shaft, a disc non-rotatably secured thereon, another disc non-rotatably and slidably secured on said shaft, a ratchet wheel rotatably mounted on said shaft 55 between said discs, and spring mechanism associated with said shaft adapted to yieldingly press said slidable disc against said ratchet wheel, and cam actuated dog mechanism to co-operate with said ratchet to 60 move said record-disc carrier mechanism forward.
15. In a record-disc lifting mechanism, 65 a frame, a vertically swinging bracket pivoted on said frame, a record gripping chuck hinged on said swinging bracket transversely to the pivot of said bracket, record gripping hooks pivoted in said chuck, mechanism within said chuck to operate said hooks, mechanism to cause said chuck to swing downwardly on its hinge, 70 and means to operate said gripping mechanism.
16. In a record-disc lifting mechanism, 75 a vertically swinging bracket, means to operate the same, a chuck hinged thereon, a spring in said hinge adapted to yieldingly maintain said hinge in a normally open position, means to operate said hinge, gripping hooks mounted in said chuck, a spring-actuated shaft mounted in said chuck, radial arms thereon, links extending from said arms to said gripping hooks, a lever pivoted in said chuck with one arm thereof projecting beyond the periphery of the chuck, a hollow hinge pin in said hinge, 80 a slidable rod in said hollow hinge pin, engaging said lever, and lever and cam mechanism to operate said slidable rod.
17. In a lifting chuck mechanism, a frame, 85 a swinging bracket pivoted on said frame, a lifting chuck hinged transversely thereon, gripping mechanism in said chuck, a slid- 90 able rod in said hinge, adapted to operate said gripping mechanism, a lever pivoted in said swinging bracket to operate said slidable rod, means to swing said bracket upwardly, a pair of bell-crank levers pivoted on said frame so one arm thereof will be on the axis of the pivot of said bracket, a link from one of said bell-crank levers to the lever pivoted in the swinging bracket, another link from the other of said bell-crank levers to an ear on the inside of said 95 chuck, and cam actuated mechanism to operate said bell-crank-lever.
18. In a machine of the class described, 100 a swinging plate adapted to be engaged by the lower edge of a record-disc, and cam and lever mechanism to cause said plate to swing toward a record-disc to tip the upper edge of the record-disc slightly forward.
19. In a machine of the class described, 105 a travelling record-disc carrier, record-discs therein, a record-disc lifting chuck, grip- 110 ping hooks pivoted therein, a swinging plate adjacent to said chuck and cam and lever mechanism to swing said plate against a record being carried to said chuck whereby the upper edge of said record-disc will be caused to swing forward against said chuck.
20. In a machine of the class described, 115 a tone arm operating mechanism, consisting of a feed-shaft, a worm sleeve thereon, gear, 120 arm, and link mechanism operated by said worm sleeve, and a swinging bracket to support the same, and a swinging lever adapted to be manually operated to main- 125

tain said gear and worm mechanism out of engagement.

21. In a machine of the class described, a tone arm operating mechanism consisting of a feed shaft, a worm sleeve thereon, gear, arm, and link mechanism operated by said worm sleeve, a swinging lever

adapted to be manually operated, a swinging stop adapted to engage and limit the movement of said gear and arm mechanism, and 10 a link connecting said swinging stop with said manually operated lever.

In testimony whereof I affix my signature.

WILLIAM T. CARNES.
